UNITED STATES PATENT OFFICE.

WILLIAM BOUCHER, JR., OF BALTIMORE, MARYLAND.

DESIGN FOR A DISPLAY COLLAR FOR A RECEPTACLE.

60,440.

Specification for Design.

Patented Feb. 21, 1922.

Application filed May 2, 1921. Serial No. 466,244. Term of patent 3½ years.

To all whom it may concern:

Be it known that I, WILLIAM BOUCHER, Jr., a citizen of the United States, residing at Baltimore, in the State of Maryland, have invented a new, original, and ornamental Design for Display Collars for Receptacles, of which the following is a specification, reference being had to the accompanying drawings, forming part hereof, in which,

Figure 1 is a front elevation of a display

collar showing my new design, a can or receptacle being shown in dotted lines; and

Figure 2 is an edge view of my new design, a can or receptacle being shown in dotted lines.

I claim:

The ornamental design for a display collar for a receptacle, as shown.

WILLIAM BOUCHER, JR.
